UNITED STATES PATENT OFFICE.

PHILIP A. KOEHRING, OF MILWAUKEE, WISCONSIN, ASSIGNOR TO KOEHRING MACHINE COMPANY, OF MILWAUKEE, WISCONSIN, A CORPORATION OF WISCONSIN.

CONCRETE-MIXER.

1,177,418.

Specification of Letters Patent. Patented Mar. 28, 1916.

Application filed December 1, 1914. Serial No. 875,027.

To all whom it may concern:

Be it known that I, PHILIP A. KOEHRING, a citizen of the United States, residing at Milwaukee, in the county of Milwaukee and State of Wisconsin, have invented certain new and useful Improvements in Concrete-Mixers, of which the following is a specification.

This invention appertains to the art of concrete mixing machines and comprises primarily a small type mixer of novel construction. By "a small type mixer" is meant a machine capable of mixing comparatively small batches of cement, sand, and other materials treated in machines of this sort, the primary object of the present improvements having been to devise a machine of the utmost simplicity whereby it may be manufactured and marketed at low cost, a machine which will be very effective in so far as its mixing functions are concerned, and one which, notwithstanding its simplicity and cheapness of structure, is possessed of all the requisites of substantiality and wear and tear resisting qualities which machines for the particular purpose must have in view of the hard usage to which they are ordinarily subjected.

In carrying out the invention, it is contemplated to mount the mixing instrumentalities upon a portable truck which carries a framework on which a mixing drum is rotatably supported, the means for mounting the drum in position and holding the same for ready rotation forming an essential feature of the improvements, together with special means provided for the purpose of facilitating the mixing action and discharging the contents of the drum of the mixing receptacle, all of which will be fully understood upon reference to the accompanying detail description and to the appended drawings, in which:

Figure 1 is a side view of a mixer embodying the invention. Fig. 2 is a plan view of the same. Fig. 3 is a side elevation looking toward the discharge end of the mixing drum; and Fig. 4 is a transverse sectional view bringing out more clearly the means supporting the drum for rotation and the mixing and discharge chute with its operating devices. Fig. 5 of the drawing illustrates a modified form of means for supporting the drum to rotate about its axis.

Throughout the following detail descrip-

tion, and on the several figures of the drawings, similar parts are referred to by like reference characters.

The truck illustrated in the drawings as carrying the mixing mechanism of the invention is made of any conventional type and preferably merely comprises the body A mounted upon the ground wheels B, any suitable draft means being connected with the front end of the truck and the front wheels B being susceptible of being turned for steering purposes, if desired. On the body A of the truck is arranged a vertical framework C composed of suitable uprights C', horizontal members C'' and crossed braces C''' that will be observed in Fig. 2 of the drawings. The framework C is disposed at one end of the truck A and adjacent to the opposite end will preferably be arranged a motor 1 of any common type, such as an explosive engine, suitable driving means being provided intermediate said motor and the mixing drum 2 mounted on the framework C, and including the drive gears 3 and 4, the latter gear meshing with the teeth of a gear ring 5 connected with the drum 2. Any suitable clutch means may be utilized whereby to interrupt and establish the driving connection between the engine 1 and the drum 2, and since this means is not material within the contemplation of the present invention, the same is not described in detail.

The means to support the drum 2 on the framework C comprises a bracket or support of approximately V-form, designated 6, and seen best in Figs. 1 and 4 of the drawings, said bracket having the upwardly divergent arms thereof secured in any substantial manner to the upper end of the framework C. The lower portion of the bracket 6 is curved sufficiently to partially enter the charging opening 7 at one end of the drum 2 and is formed with a bearing 8 in which is mounted the journal member 9 pinned or otherwise secured to said bearing as shown at 10. The journal member 9 projects quite a little distance into the drum 2 and mounted to rotate freely on the projecting portion is a sleeve-like member constituting a hub 11 of a spider 12 the latter consisting of radiating arms as usual, said arms being formed integral at their outer terminals with the gear ring 5.

It will be seen from the foregoing, that

the drum 2 is supported therefore upon the journal member 9 and is free to rotate with said journal member as its axis, during the operation of the driving means connecting 5 said drums with the engine 1. Displacement of the drum 2 from the axial support of the same is prevented by means of a plate 13 attached to the inner end of the member 9 by screw 14, the plate being of sufficient 10 diameter to overlap the innermost portion of the hub 11 and thus hold the drum 2 in operative position. In order to protect the securing means 13-14 a cap 15 is fastened to the inner end of the hub 11 so as 15 to house the portions of the parts 13-14 which would be otherwise exposed, and contact of the materials mixed in the receptacle 2, with the parts 13 and 14 is prevented in this way. The cap 15 is secured to the 20 member 11 by any suitable fastenings.

The drum 2 is preferably made in sections including end sections 16 and a middle section 17 one of the end sections 16 and the middle section 17 being connected together 25 by means of the spider 12 owing to the fact that the gear ring 5 forming a part of said spider has the lateral flanges 5' riveted or otherwise secured to the particular parts of the drum just referred to. The radiating arms comprising the member 12 incline slightly toward the center of the drum, the mounting of the latter so far as stability is concerned being subserved by the above feature of construction and the fact that the 30 support about which the drum revolves projects as near to the center of gravity of the receptacle as is practicable having in view the mixing function of the drum.

Interiorly the drum 2 will, of course, be 40 provided with suitable mixing buckets 18 and a stationary charging chute 19 is located at the inlet end of the drum and suitably secured at opposite portions thereof, to the adjacent uprights C' of the framework C. 45 It is desirable since the materials to be mixed are introduced into the drum at the end adjacent to the supporting bearing or hub 11 to protect these parts from wear incidental not only to the introduction of the said material or incident to the mixing of the materials 50 after being received in the receptacle 2. For the above purpose a guard 20 is provided and consists of a casing inclosing the portion of the hub 11 intermediate the arms 55 of the spider 12 and the bearing 8 of the bracket 6.

At its discharging end, the drum 2 is provided with the usual opening for discharge purposes and a reversibly inclinable chute 21 60 is pivoted at 22 to brackets projecting inward from certain uprights of the framework C. The chute 21 is manually operable by means of the provision of a shaft 23 mounted in bearings on the framework C, 65 said shaft having arms 24 connected by

links 25 with the outer portion of the chute 21. By manipulation of a handle or lever 26 at one end of the shaft 23, the arms 24 may be raised or lowered and when raised the links 25 will be lifted to move the chute 70 21 to a position in which it inclines downward into the drum 2. In such position the chute co-operates in the mixing operation to carry the mixed materials back toward the inlet or charging end of the drum. The 75 chute 21 is furthermore held in the position just mentioned, as seen in dotted lines in Fig. 4, by the provision of curved ends or hooks 25' on the upper portions of the links 25, said portions adapted to engage over the 80 shaft 23 and sustain the chute at the adjustment referred to. When the chute is inclined in a reverse manner, as seen by full lines in Fig. 4, the mixed materials carried upward by the buckets 18 of the drum are 85 permitted to fall into the chute and are thus discharged therefrom into a suitable receptacle or the like.

If desired, a suitable casing may be provided for the engine 1, this matter not being 90 essential to the invention, however, since any driving means whatever may be utilized for the drum 2.

In Fig. 5 of the drawings, there is illustrated a modification of the invention in respect to the means employed for supporting the mixing drum for rotation about its axis. In this construction, the journal member 9^a is carried by the spider 12^a being keyed or otherwise secured to the central 95 portion of the latter and fits into the opening at the lower end of the bracket 6^a, said opening forming a bearing in which the journal member is free to rotate. The securing means to prevent displacement of the 100 journal member from its bearing is located in the modified construction at the outer end of the journal member instead of at its inner end as shown in Fig. 4. Said securing means includes a nut or collar 13^a over 105 which fits the cap 15^a affording a housing for said member 13^a and held in place by any suitable fastening device. The casing element shown at 20 in Fig. 4 is equivalent to the hollow casing extension 20^a seen in 110 Fig. 5, the part 20^a being preferably integral with the spider 12^a at the hood portion of the latter and overlapping the bearing portion of the bracket 6^a which is 115 formed with a groove shown at 6^b in which 120 that portion of the extension 20^a uppermost during the rotation of the drum operates. The member 20^a is effective to prevent the materials mixed in the drum from 125 in any way interfering with the bearing for the member 9^a. Either of the methods described for mounting the drum upon the bracket supporting the same may be employed within the purview of the invention. It is contemplated to utilize the spider 12 130

or 12^a as the case may be to perform a function additional to those previously ascribed thereto, namely as a means to support certain of the mixing blades 18 in the drum 2, such blades being riveted or otherwise secured to the arms of the spider adjacent to the outer ends of the latter.

Having thus described my invention, what I claim as new is:

- 10 1. In a mixing machine, the combination of a drum having an end opening, mixing devices in said drum, a support for the drum comprising a framework, a bracket carried by the framework and terminating adjacent 15 to said end opening of the drum, a journal member carried by said bracket, and projecting into the end opening of the drum, means supporting the drum and having a bearing to receive said journal member, and 20 a casing surrounding said bearing for preventing materials mixed in the drum from wearing upon the bearing.

2. In a mixing machine, the combination of a drum having an end opening, a support for the drum comprising a framework, 25 a bracket carried by the framework and terminating adjacent to said end opening of the drum, a journal member carried by said bracket, and projecting into the end opening of the drum, means supporting the 30 drum on said journal member comprising a spider attached at its outer portion to the drum and supported at its inner portion by the journal member, mixing members connected with the drum and spider, and a 35 casing between said bracket and the spider extending around the journal member for the purpose described.

In testimony whereof I affix my signature in presence of two witnesses.

PHILIP A. KOEHRING.
